UNITED STATES PATENT OFFICE.

JOSEPH B. MORAN, OF SAN FRANCISCO, CALIFORNIA.

WATER-HEATER.

1,183,100.

Specification of Letters Patent.

Patented May 16, 1916.

Application filed September 15, 1915. Serial No. 50,806.

To all whom it may concern:

Be it known that I, JOSEPH B. MORAN, a citizen of the United States, residing in the city and county of San Francisco and State 5 of California, have invented new and useful Improvements in Water-Heaters, of which the following is a specification.

This invention relates to a water heater.

One of the objects of the present invention is to provide a simple, substantial 10 cheaply manufactured water heater of the instantaneous heater type, which is particularly constructed to produce a large heating area together with means for insuring 15 a rapid and forced circulation of water within the heater in one direction.

Another object of the invention is to provide means which will permit collection of 20 precipitates, such as sediment and the like without clogging the heating surfaces or in 25 any way interfering with the circulation.

Further objects will hereinafter appear.

The invention consists of the parts and 25 the construction and combination of parts, as hereinafter more fully described and 30 claimed, having reference to the accompanying drawings in which—

Figure 1 is central, vertical section of the 35 heater. Fig. 2 is a plan section on line 2—2, Fig. 1.

Referring to the drawings in detail it 40 will be seen, that the heater comprises a casing of circular shape, consisting of two cone-shaped disks 2 and 3, which may be sealed together at the periphery by welding, 45 brazing, screws or any other suitable means. The disks are preferably flattened as much as possible, to produce a shallow chamber 50 interior thereof, of considerable area.

Suitably secured either to the upper or 55 lower disk, is a cone-shaped baffle plate 4; this is mounted in a position with relation to the lower disk 3, so as to produce a narrow, 60 annular passage 5, through which the water must pass before it can enter the main chamber 6, or escape through the discharge opening 7. The baffle plate is of smaller diameter 65 than the interior periphery of the chamber and as it is spaced from the lower disk 70 3, an annular unrestricted discharge passage will be formed, as at 8 which communicates with chamber 6. In the present instance, 75 the baffle plate is shown as provided with a plurality of radially disposed foot members 9; these being provided for the purpose of 80 securing the baffle plate to one or the other

of plates 2, or 3. Water from any suitable source is admitted from a pipe 10, through the lower disk 3 and will here strike the apex of the cone-shaped baffle plate 4; this causes the water to become deflected and distributed in all directions and will, in this manner pass between the baffle plate and the lower disk 3, in a comparatively thin film, before it is permitted to enter the main 60 chamber 6, or escape through pipe 7.

The heater as a whole, may be placed directly above a gas burner or any other form of burner, not necessarily here shown, and when thus positioned, it can readily 70 be seen that the thin film of water will be instantly heated, thereby causing a rapid and forced circulation in the direction indicated. Several units, such as indicated in Fig. 1, may be connected together and 75 surrounded by a casing and connected with a hot water tank or the pipe line service of a building. The heater may also be installed in flues or attached to other forms of heaters to utilize waste heat and act as boosters to 80 insure a rapid circulation. The provision of the baffle plate 4, is of great importance, as it first of all permits a thin film of water to be exposed to the heating surface. It furthermore, insures rapid circulation and 85 also acts as a mud drum to collect any mud or sediment contained in the water. The sediment collecting on the inside of the baffle plate which in this instance forms a false bottom for chamber 6, does not interfere with circulation of the water through 90 the heat unit, nor does it affect or clog the heating surfaces in any manner, as the baffle plate is spaced from and supported above the main heating surface. The shape of the 95 heater, furthermore presents a great area and while the surface 3 is more directly exposed to heat than the surface of plate 2, it will be seen that both surfaces or plates will transmit heat to the water. The provision of the baffle plate makes it impossible 100 for water to pass directly through the heater, as is common in many forms of heaters.

The materials and finish of the several 105 parts of the device may be such as the judgment and experience of the manufacturer may dictate.

I wish it understood that various changes in form, proportions and minor details of 110 construction may be resorted to within the scope of the appended claims, and that I do

not wish to limit myself to the specific design and construction here shown.

Having thus described my invention, what I claim and desire to secure by Letters Patent is—

1. In a water heater, a chamber, having a top and bottom, an inlet pipe at the center of the chamber bottom, an outlet pipe at the center of the chamber top, and a cone-shaped baffle plate between the top and bottom extending over the inlet pipe, said baffle plate having its concave side facing the outlet whereby said concave side will form a mud collecting pocket.
- 15 2. In a water heater, a chamber formed of a pair of cone-shaped plates secured together, an inlet and an outlet at the respective apices of the plates, and a cone-shaped baffle plate having its apex presented to the inlet and disposed to form a relatively shallow passage in conjunction with the adja-

cent chamber plate, the concave side of the baffle plate being presented to the outlet to form a mud collecting pocket.

3. In a water heater, a chamber having a top and bottom, an inlet pipe at the center of the chamber bottom, an outlet pipe at the center of the chamber top, and a combined baffle and mud collector between the inlet and outlet arranged to trap sediment carried by the water in the passage of the latter from the inlet over the baffle to the outlet and to spread the water in a comparatively thin film.

In testimony whereof I have hereunto set my hand in the presence of two subscribing witnesses.

JOSEPH B. MORAN.
